ATTORNEY

UNITED STATES PATENT OFFICE

CLINTON E. MARSHALL, OF NEW YORK, N. Y.

PEN AND PENCIL CLIP

Application filed January 15, 1930. Serial No. 420,375.

This invention relates to spring clips such as are used in connection with pens, pencils and similar articles, and particularly to the manner of arranging and mounting the clip in connection with its support; and the object of the invention is to provide a clip of the class specified, one end of which is provided with downwardly and laterally extending flanges adapted to be passed through a relatively large aperture in the support in connection with which the same is to be mounted, and then moved into proper position with respect to the support and retained in such position by a member inserted into the support and engaging the flanges of the clip to securely clamp the same in position; a further object being to provide a clip of the class specified which may be mounted in position without any expensive or time taking operations such as pinning, riveting, bending or the like and without the use of any special tools or implements of any kind or class whereby the cost of manufacture of the clip and of the resulting product with the clip attached thereto may be materially reduced; and with these and other objects in view, the invention consists in a device of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a sectional side view of a fountain pen cap showing one of my improved clips mounted in connection therewith.

Fig. 2 is a section on the line 2—2 of Fig. 1.

Fig. 3 is a plan view of one end of the cap indicating the manner of coupling the clip therewith; and,

Fig. 4 is a plan view of the clip detached.

To illustrate one use of my invention, I have shown the clip applied to a fountain pen cap. It will be understood however that the same may be mounted in connection with tubular bodies of any kind or class. In the

drawing 5 represents a support or cap which, in carrying my invention into effect, is provided with an elongated aperture 6 extending longitudinally of the cap and arranged adjacent the closed end 5a thereof. At 7, I have shown one of my improved clips which is formed from a single sheet of metal, one end being fashioned into a ball or knob 8 and the other end terminating in a tongue 9 which is arc-shaped in cross sectional form. Inwardly of the tongue are downwardly extending flange walls 10 which terminate in laterally extending mounting flanges 11 which are of the form illustrated in Fig. 4 of the drawing.

The transverse dimensions of the clip where the flange walls are located, are equal to the transverse dimensions of the aperture 6 so as to fit snugly therein. In assembling the clip the end thereof is passed through the aperture 6 in the manner indicated in Fig. 3 of the drawing with the flange walls 10—11 arranged longitudinally with respect to the aperture and when fully positioned within the chamber of the cap, the clip is turned into a position at right angles to that shown in Fig. 3 and then moved upwardly and outwardly to pass the walls 10 and top of the clip upwardly through the aperture 6 and to bring the flanges 11 into engagement with the inner wall of the cap 5 and to arrange the tongue 9 forwardly of the end 6a of the aperture after which the clip is moved backwardly to arrange the tongue end 9 upon the outer surface of the cap beyond the end 6a of the aperture as clearly seen in Fig. 1. This operation may be facilitated in placing the retaining plug 12 in the bore of the cap, which plug serves to engage the flanges 11 and securely support or retain the attached end of the clip against movement with respect to the cap 5.

This position of the parts is clearly seen in Fig. 2 of the drawing.

In the construction shown, the plug 12 is tubular in form. However, my invention is not necessarily limited to any particular type or form of plug except in the necessity of its engaging the flanges 11 to firmly retain the clip in position.

Between the attached end of the clip and the knob 8, the clip is tapered to form a

100

spring arm which causes the spring proper to clip as in other devices of this class, it being understood that the distinctive feature of my invention resides in the manner of forming the attached end of the clip and the method of mounting the same in connection with the cap or other support.

In the art to which my invention relates, it has been customary to pin or rivet a clip to a support or to pass two or more lugs or flanges through two or more apertures formed in the support and then bend, flare or rivet said lugs to retain the clip in position whereas with my present construction, all of such operations are obviated. In other words, the attaching end of the clip is completely formed and assembled or coupled with its support in the manner disclosed, and when assembled, the clip will produce a neat and finished appearance and will be strong and durable in use.

In this connection, it will also be understood that the end wall of the clip which overlies the wall of the support adjacent the aperture 6 may be given any contour or design, the same being rounded or arc-shaped in the construction shown. It will be apparent that various changes in and modifications of the construction herein shown and described may be made within the scope of the appended claims without departing from the spirit of my invention or sacrificing its advantages.

Having fully described my invention, what I claim as new and desire to secure by Letters Patent, is:

1. A device of the class described comprising in combination with a tubular support having an elongated aperture therein, a clip, one end of which is provided with downwardly and laterally flared flanges, said end of the clip being coupled with the support by passing the same through said aperture to arrange said flanges in position to engage opposed walls of the aperture and the inner wall of said support, means mounted in said support cooperating with said flanges for retaining said clip against displacement with respect to said support, and a projecting tongue on said end of the clip overlying the support adjacent said aperture.

2. A clip for a tubular support, said support having an elongated aperture in the wall thereof and opening into the bore of said support, one end of the clip having side flanges extending through said aperture and engaging the inner wall of the support at opposite sides of the aperture, a member inserted in the bore of the support and cooperating with said flanges for retaining the clip against displacement with respect to the support, and a projecting member on said end of the clip overlying the outer wall of the support adjacent the aperture therein.

3. A clip for attachment to a tubular sup-

port having an elongated aperture arranged in one wall thereof, comprising an elongated body, one end of which is provided with a knob and the other end being fashioned to form a mounting plate, said plate having inwardly of the end thereof, relatively short depending side walls, corresponding in width to the thickness of the wall of said tubular support and terminating in laterally extending flanges, and the free end of said plate extending beyond the flanges to form a tongue.

4. The combination with a fountain pen cap of an elongated aperture arranged in the side wall of the cap adjacent the closed end thereof, a clip, one end of which is of substantially the same transverse dimensions as the transverse dimensions of said aperture, said clip including laterally extending side flanges adapted to be arranged to engage the inner surface of the bore of said cap, a plug member inserted into said bore inwardly of said flanges and adapted to firmly clamp said flanges between the same and the wall of said cap to retain the clip against displacement with respect to the cap, and said end of the cap including a projecting tongue adapted to overlie the outer wall of the cap at one end of the aperture.

5. The combination with a fountain pen cap of an elongated aperture arranged in the side wall of the cap adjacent the closed end thereof, a clip, one end of which is of substantially the same transverse dimensions as the transverse dimensions of said aperture, said clip including laterally extending side flanges adapted to be arranged to engage the inner surface of the bore of said cap, a plug member inserted into said bore inwardly of said flanges and adapted to firmly clamp said flanges between the same and the wall of said cap to retain the clip against displacement with respect to the cap, said end of the cap including a projecting tongue adapted to overlie the outer wall of the cap at one end of the aperture, and the other end of the clip having an enlarged member joined to the first named end of the clip by a spring arm.

In testimony that I claim the foregoing as my invention I have signed my name this 10th day of January, 1930.

CLINTON E. MARSHALL.
